UNITED STATES PATENT OFFICE.

FRANK P. J. PATENALL, OF BALTIMORE, MARYLAND.

RAILROAD SIGNALING.

1,117,899.

Specification of Letters Patent. Patented Nov. 17, 1914.

Application filed July 15, 1910, Serial No. 572,142. Renewed April 17, 1914. Serial No. 832,633.

To all whom it may concern:

Be it known that I, FRANK P. J. PATEN-
ALL, a citizen of the United States, residing
at Baltimore, in the State of Maryland,
5 have invented certain new and useful Im-
provements in Railroad Signaling; and I
do hereby declare the following to be a full,
10 clear, and exact description of the same, ref-
erence being had to the accompanying draw-
ings, forming a part of this specification,
and to the figures and letters of reference
marked thereon.

This invention relates to improvements in
signals for controlling the running of rail-
15 way trains and is particularly applicable to
those systems making use of semaphore
arms or signal blades which by their po-
sition indicate to the engineer of the train
20 track conditions ahead, or which govern the
running of the train.

In signaling systems as now employed
there is a material limitation to the infor-
25 mation which may be imparted to the engi-
neer by the positioning of the signal or
semaphore arms and considerable confusion
25 has arisen because of the impracticability of
making the signals of automatic and manual
control systems uniform in their indica-
tions.

30 A further confusion and source of danger
is found to exist in present systems because
of the liability of mistaking contiguous
lights for the signal lights in night oper-
35 ation of trains, this danger being accentu-
ated by the fact that in most of the present
signaling systems the clear night indication
is given by a white light which substan-
tially corresponds in appearance to the light
40 given by ordinary illuminating means or
lanterns such as are used about railway
stations and populous centers through which
the track may run.

The present invention has for its object
45 to overcome many of the objections found
to exist in railway signaling systems as at
present in use, and while in some respects it
conforms thereto, yet in its major aspects it
differs very widely therefrom, more espe-
50 cially in regard to the possibility of convey-
ing accurate and unmistakable information
of widely varying character to the engineer
and in overcoming the liability of dangerous
error either through the false reading of the
55 signals or of the accidental or unintentional
operation of the signals through accident or
breakage.

The invention consists in certain novel
details of construction and combinations
and arrangements of the parts of the sig-
60 naling apparatus, and in certain novel and
arbitrary positioning of the signaling mem-
bers whereby errors through breakage or
false or incorrect reading of the signals are
necessarily on the side of the safety.

Referring to the accompanying drawings 65
Figures 1 to 4, inclusive, are elevations of a
semaphore support, and semaphore arm,
constructed in accordance with and embody-
ing the mechanical features of the present
70 invention, the semaphore arm being shown
in various positions to which it may be
moved to convey the desired information to
the engineers of running trains.

In said drawings, the letter A indicates a
semaphore support which may be in the 75
form of an ordinary mast having upon its
upper end a semaphore bearing or bracket
B. Journaled in the bracket at one side of
the mast is the casting or spectacle frame D.
The mast also carries means for supporting 80
a lamp or light at C, with which the round-
els E', E², E³ will register when the spec-
tacle casting is swung upwardly around its
axis G.

Attached to the spectacle casting D is a 85
semaphore arm F, the construction and rela-
tive position of the casting and semaphore
arm F being such that either the casting
alone or the casting arm will gravitate to a
90 pendent position below the axis with the
arm substantially vertical, as shown in Fig.
1. In any other position of the casting and
arm the predominance of both weight and
exposed area is transversely removed from
95 the vertical plane of the axis and, conse-
quently, gravity acting upon the casting and
arm as well as upon accumulations of snow
or ice thereon, will always tend to move said
parts down to the position shown in Fig. 1,
100 where the arm is substantially vertical and
below the axis. With this object in view it
will be noted that the casting and arm are
not rotated upwardly beyond an inclined po-
sition above the horizontal, as shown, for
105 instance, in Fig. 4.

The roundels are arranged in a segmental
series in the casting and those shown are
adapted to contain colored glass, as for in-
stance, the roundel E' may contain yellow
glass; F² green glass, and E³ red glass, but
110 when in normal position pendent below the
axis the light C is exposed above the casting

or shows a white light, and this condition should be maintained even though additional roundels are employed, in which case the roundel in front of the light, when the casting and arm are pendent, should contain only clear glass.

The position of the semaphore arm with respect to the casting and axis on which the casting and arm are pivoted is important in 10 the attainment of the objects herein sought, and it will be noted that said arm projects beyond the casting in a line which is substantially parallel with a line which would intersect the axis and the intermediate 15 roundel or which would intersect the axis and substantially the center of gravity of the casting and it is obvious that if this relative angle of the arm with respect to the casting be preserved the location of the 20 arm on the casting is not of prime importance as said arm may be displaced bodily in one direction or the other as preferred by any particular engineer or company making use of the signal, but the location of 25 the arm, as shown, on the end of the casting away from the support is preferred, as it then hangs parallel with the support but removed therefrom sufficiently far to present a distinct appearance.

30 In accordance with the present invention the semaphore arm when in its vertical pendent position below the axis indicates danger or that the train must be brought to a standstill, thus, the stop position of 35 the arm, as shown in Fig. 1 is contrary to signals now in use where the vertical position of the arm indicates proceed or track clear. From the position shown in Fig. 1, the arm is swung up to the position shown 40 in Fig. 2, *i. e.*, diagonal below the horizontal to indicate proceed with great caution or to a horizontal position, shown in Fig. 3, to indicate proceed with caution prepared to stop at next signal, or to a position diagonally above the horizontal, as shown in Fig. 45 to indicate that all restrictions are removed and that the train may proceed at highest speed.

In all positions of the casting and blade 50 when swung away from the safe or pendent position below the axis, the preponderance of weight and exposed surface is transversely at one side of the axis and consequently any accident such as the breakage 55 of stops, failure of operating mechanism, etc., can only result in a restoration of the parts to stop position. The running instructions are all conveyed by positive angular positioning of the arm, the restrictions 60 on the running of the trains being successively removed by successive positions upwardly from the pendent position, thus failure of operating connections for any position can only result in a position of the arm 65 imposing greater restrictions on the run-

ning of the train and, consequently, greater safety necessarily results. Failure to receive running instructions by the angular positioning of the arm above the vertical, means that the train must be brought to a stop and consequently even the entire destruction of the blade would result in stopping the train and no accident could occur such as has occurred in present practice where the engineer, failing to see any signal, 75 properly presumed that it is in vertical or clear position down beside the support.

For night work and contrary to ordinary practice a white light indicates stop, thus, if error be made by confusion of the signal 80 light with adjacent lights, it can only result in bringing the train to a stop.

For indicating the successive removal of restrictions on the running of the trains the roundels brought successively in front of 85 the light are preferably of colors which are of successively increasing distinctive value. The red which is of the highest distinctive value indicates that all restrictions are removed; green that some restrictions are imposed, and yellow that the greatest caution 90 must be exercised or that the engineer must be prepared to stop within the range of vision.

The roundels or colored lights in the spectacle casting give positive information similar to that of the semaphore arm, thus when in the 45° position above the horizontal, a red glass is interposed before the light, while in the horizontal position a green 100 glass may be interposed and in the 45° position below the horizontal a yellow glass may be interposed. Obviously, the colors of the roundels taken in connection with the positions of the semaphore arm is of considerable importance, for it is intended by said colors to impart to the engineer positive information for night running, and to inform him that no restrictions are imposed, 105 a color of the highest indicating value, such as red, should be employed, especially as such color is not likely to be confused with surrounding or adjacent lights and as restrictions are imposed upon the running of the train the colors of the light may be of 110 less and less indicating value proportionally to the restrictions imposed, for as restrictions are imposed the less danger there is of an accident occurring, through failure 115 of the engineer to hold the train in proper control.

In the present invention it will be noted that the stop indication instead of being a horizontal position, as in ordinary practice, is a vertical position pendent below the axis 125 of the semaphore arm, whereby the maximum safety is secured. This is the position of the signal assumed under the influence of gravity, even though all stops or counterweights or other controlling means should 130

be eliminated, and is logically the position where the signal should indicate "stop". No load which may accumulate upon the casting or blade can by any possibility cause 5 the same to assume a position where it will give running instructions but will invariably tend to move the signal to a position indicating that the train must be brought to a standstill and the same is true even though 10 the blade and casting be broken off, for without positive running instructions indicated by the angular position of the blade an engineer is not authorized to proceed beyond the signal, and if he does so he is proceeding 15 without instructions.

Having thus described my invention, what I claim as new and desire to secure by Letters Patent of the United States, is:

1. The combination with a semaphore 20 support, of a spectacle casting pivotally mounted on said support projecting on one side of its axis and adapted to move by gravity to a pendent position below its axis, a semaphore arm held by the casting and 25 extending downwardly in substantially vertical position when the casting is pendent, the preponderance of both weight and exposed surface of both the casting and arm being on the same side of the axis when the 30 arm is in any position other than its pendent vertical position, whereby the force of gravity and any accumulation of snow or ice on either the casting or blade always 35 tend to return the arm to pendent vertical position.

2. The combination with a semaphore support, of a spectacle casting pivotally mounted on the support and projecting on 40 one side of its axis whereby it will move by gravity to a pendent position, and a sema-

phore arm secured to and projecting on the same side of the axis beyond the casting substantially parallel with a line passing through the axis and center of gravity of the casting.

3. The combination with a semaphore support, and a spectacle casting pivotally mounted on the support, projecting on one side of its axis and having a plurality of roundels therein, of a semaphore arm secured to and projecting on the same side of the axis beyond the casting substantially parallel with a line intersecting the pivotal axis of the casting and center of an intermediate roundel, whereby the preponderance 45 of weight and exposed surface of both the casting and arm will be at one side of the axis and accumulations of ice or snow on the casting or arm will tend to move the same into vertical or danger position below 50 the axis.

4. The combination with a semaphore support and a spectacle casting having roundels therein, said casting being pivotally mounted on the support, and projecting at one side of the axis and movable about said axis in an arc greater than 90°, of a semaphore arm secured to said casting and projecting downwardly in vertical position when the casting is pendent below the 65 axis and projecting diagonally upward when the casting is swung to its highest position, the center of gravity of both the casting and arm and the preponderance of exposed surface being on one side of the axis when the 70 casting is in its highest position.
